CLAIM

The ornamental design for a contoured electrical foot heating pad, as shown and described.

DESCRIPTION

FIG. 1 is a top plan view of a contoured electrical foot heating pad showing my new design;

FIG. 2 is a bottom plan view thereof;

FIG. 3 is a rear view thereof;

FIG. 4 is a left side view thereof;

FIG. 5 is a right side view thereof; and,

FIG. 6 is an isometric view thereof.

Portions of the contoured electrical foot heating pad have been shown broken to indicate indeterminate length. The indeterminate portion of the article forms no part of the claimed design. Patentability is based only on those portions of the contoured electrical foot heating pad that are shown in solid lines.
